UNITED STATES PATENT OFFICE.

FLOYD E. KUNZMAN, OF JOHNSON CITY, NEW YORK, ASSIGNOR TO SAMUEL D. LEAD-BEATER, OF JOHNSON CITY, NEW YORK.

SPARK INTENSIFIER.

Application filed February 21, 1923. Serial No. 620,473.

To all whom it may concern:

Be it known that I, FLOYD E. KUNZMAN, a citizen of the United States, residing at Johnson City, in the county of Broome and State of New York, have invented certain new and useful Improvements in Spark Intensifiers, of which the following is a specification.

This invention has reference to spark intensifiers designed to materially intensify the voltage of the current flowing through the intensifier to produce an increased spark where the latter is wanted.

If a current of electricity be caused to traverse a conducting path and the continuity of such path be broken at a given point, the voltage of the current of electricity flowing through the path will be largely magnified with the result that a correspondingly magnified spark is produced, such increased spark being readily apparent at the sparking points of the spark plug used with the result that the spark obtained is very materially magnified or fattened with the result that a much more pronounced spark at the spark points of the spark plug, is obtained with increased effect so that a much more certain explosion occurs than when the intensifier is absent.

The invention will be best understood from a consideration of the following detailed description taken in connection with the accompanying drawing forming part of this specification, with the understanding that the invention is not confined to any strict conformity with the showing of the drawings, but may be changed and modified so long as such changes and modifications mark no material departure from the salient features of the invention as expressed in the appended claims.

In the drawings:—

Figure 1 is a plan view of the intensifier attachment.

Fig. 2 is a side elevation of the intensifier attachment as applied in circuit with a spark plug and one of the circuit terminals thereof.

Fig. 3 is a section on the line 3—3 of Fig. 1.

Referring to the drawings, there is shown a spark plug 1 which may be taken as typical of any approved type of spark plug such as is employed in connection with explosion

engines and hence no particular description thereof is needed.

Associated with the spark plug 1 is a block 2 of insulation, such for instance as hard rubber or vulcanized fiber, or some other such material.

Entering the block 2, there are arranged two conducting strands 3, 4. These two strands are spaced apart lengthwise of the block 2, with each strand intermediate its ends, being bent to provide entering and leaving legs 5, 6, separated by a space greater than the jumping distance of the current employed, with each strand having one end fixed. The outer end terminals 7 are provided with ring members 3' for connection to a source of current of suitable character to cause the jumping of a spark between overlapping terminals 8 which are within sparking distance of each other and each of these terminals 8 are of arcuate contour and disposed at an angle with respect to the surface of the body 2 in which the intermediate portions are embedded, both surfaces of which body are covered with a sheet 9 of vulcanized rubber or some other suitable insulating material.

The terminals 8 are curved relative one to the other to bring them well within the sparking distance, while the portions of the conductors 3, 4, 5 and 6 where they are exposed are far enough apart to prevent the jumping of the spark between them in preference to passing between the end terminal portions 8 which are separated only by air insulation and not by the composition of the block 2.

By providing the conductors 3 and 4 with terminals 8 in the manner described, the difference of potential between any near points of these conductors is too small to cause the jumping of the current except at the extremities of the terminals 8 so that there is no danger of sacrificing any of the advantages of the arrangement of the terminals, and consequently the spark will jump at only the point between the close approach of the terminals 8.

What is claimed is:—

1. In a spark intensifier, a body of insulation, conducting elements each having a portion intermediate its ends embedded in said body, the inner end terminal portion of each of said elements being of arcuate contour

and disposed at an angle with respect to the surface of the body in which the intermediate portion is embedded, said terminal portions further being spaced one from the other to provide a spark gap, and attaching means for said elements carried at the outer ends thereof, the said intermediate embedded portion of each element being positioned within the body of insulation at the longitudinal center thereof, and each embedded portion further being located between the center and ends of its respective portion of the body, the inner end terminal portion further extending in opposite directions and offset with respect to the central longitudinal axis of the body.

2. In a spark intensifier, a body of insulation, conducting elements having a portion

intermediate its ends embedded in said body, the inner end terminal portion of each of said elements being of arcuate contour and disposed at an angle with respect to the surface of the body in which the intermediate portion is embedded, said inner end terminal portions further being in overlapped relation one to the other and offset with respect to the central longitudinal axis of the block and directed inwardly and downwardly toward the longitudinal center of the body to provide a spark gap, and attaching means for said elements carried at the outer ends thereof.

In testimony whereof, I affix my signature hereto.

FLOYD E. KUNZMAN.
